UNITED STATES PATENT OFFICE.

ABNER JUDSON MCGEHEE, OF JACKSON, TENNESSEE.

DESIGN FOR A SHADE-ROLLER HOLDER.

SPECIFICATION forming part of Design No. 34,501, dated May 14, 1901.

Application filed March 28, 1901. Serial No. 53,364. Term of patent 14 years.

To all whom it may concern:

Be it known that I, ABNER JUDSON MCGEHEE, a citizen of the United States, residing at Jackson, in the county of Madison and State 5 of Tennessee, have invented and produced a new and original Design for Shade-Roller Holders, of which the following is a specification, reference being had to the accompanying drawings, forming a part thereof.

Figure 1 is a plan view of a shade-roller holder, showing the general outline of my design with its apertures. Fig. 2 is a sectional view of the same.

As shown in the drawings, the leading or 15 material features of my design consist of a bottom lobe A, a tapering stem B, and a top lobe C, the two lobes being circular in outline and of different diameters, the connecting-stem B being tapered in proportion to the

relative sizes of the two lobes. Lobe C has 20 an aperture therein, designated as 1, consisting of a circle with a slot projecting therefrom. Lobe A has an aperture marked 2, consisting of a slot with the shoulders therein, as clearly shown in the drawings. 25

Having described my invention, what I claim as new, and desire to secure by Letters Patent, is—

The design for a shade-roller holder as shown and described. 30

In testimony whereof I have signed my name to this specification in the presence of two subscribing witnesses.

ABNER JUDSON MCGEHEE.
